UNITED STATES PATENT OFFICE

WILLIAM GEORGE CLARK, OF VANCOUVER, BRITISH COLUMBIA, CANADA

SMOKING PIPE

Application filed January 21, 1931. Serial No. 510,237.

This invention relates to certain new and useful improvements in smoking pipes and it particularly has for its object to provide a pipe with a simple and effective means for condensing and trapping saliva so that only the dry smoke will pass through the mouth piece.

Further, the invention has for an object to provide a smoking pipe characterized as above which, to all outward appearances, does not differ from the ordinary pipe in which the bowl and stem are integral and the mouth piece is separable from the stem.

Further, the invention has for its object to provide means whereby the condensed and trapped saliva is collected in a removable receptacle located in the stem and in which the parts are so coordinated and cooperatively arranged that accumulations of saliva in the chamber of the stem around the collection receptacle or between it and the bowl end of the stem's chamber are avoided.

Further, it is an object to provide a smoking pipe characterized as above in which the saliva collection receptacle is designed to cool the smoke as it passes through, thereby delivering the smoke dry and with the full flavor of the tobacco used.

A further object of the invention is to provide means whereby the pipe may easily be cleaned and to so construct the saliva collection receptacle that it can be withdrawn from the pipe stem even though it fit the stem in a manner causing more or less retaining friction.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claim, reference being had to the accompanying drawing, in which:—

Figure 1 is a side elevation of my improved pipe.

Figure 2 is an enlarged vertical longitudinal section of a portion thereof.

Figure 3 is a cross section on the line 3—3 of Figure 2.

In the drawing in which like numerals of reference indicate like parts in all of the figures, 1 represents the bowl which has the usual tobacco chamber 2 and the usual stem 3, the latter in this case being provided with a cylindrical bore or chamber 4 entering from the outer end of the stem.

5 is the mouth piece which is provided with the usual stopper 6 to fit into the outer end of the stem 3 in a manner to be frictionally retained or the two parts may be screwed together if desired, this construction being common practice. The mouth piece 5 has the usual smoke duct 7 and in this case it is counterbored at 8 to receive a short tube 9 which projects beyond the end of the stopper 6 into the tubular receptacle 11.

The tubular receptacle 11 is closed at one end by a permanent wall 12 and is of such a length that when the parts are assembled (see Figure 2) the wall 12 will lie against the bottom wall 13 of the chamber 4, while the open end of the receptacle 11 will abut and be closed by the stopper 6.

The receptacle 11 has a shallow longitudinal groove 14 extending from end to end at its highest level and the groove 14 registers with a port 15 of approximately the same area as the cross section of the groove, for effecting communication between the smoke chamber 2 and the groove 14.

Adjacent the stopper 6 the receptacle 11 is apertured at 15 to provide a port for passing the smoke from the higher end of the groove 14 into the interior of the receptacle 11, the short tube 9 projecting into the receptacle beyond the place where the port 15 is located so as to cause a reverse flow of the smoke and trap the condensate in the receptacle 11, which condensate gravitates toward the lowest point of the receptacle. It is to be noted that the preferable construction of my pipe requires that the receptacle 11 be of substantially the length of the chamber 4 between the wall 13 and the end of the stopper 6 so that there will be no space between the walls 12 and 13 in which matter may accumulate, thus keeping the bore 14 always clean.

The location of the hole 15 adjacent the outer end of the receptacle 11 enables a hook to be inserted after the mouth piece has been taken off and the receptacle pulled out, it of course being understood that the receptacle is preferably held in place by retaining friction with the groove 14 in register with the port or passage 10.

While I prefer to locate the opening 15 a slight distance from the end of the receptacle 11 in order that it may take a hook for pulling the receptacle out, it may be located at the extreme edge if desired, as the exact location of the opening 15 with relation to the extreme 15 end of the receptacle 11 is not essential. This location may be shifted as may be found desirable. It should, however, be located in such a position as to be between the exposed end of the tube 9 and the end of the stopper 6 20 in order that the reverse flow of the smoke may be had.

I am aware that attempts have been made to provide pipes with devices for trapping the saliva but such pipes as have come to my 25 attention, are too expensive and complicated in their construction and arrangement, and furthermore such pipes, by virtue of their peculiar constructions, leave pockets in the bowl or stem portion of the bowl in which saliva 30 and other matter can accumulate and in time clog the action of the pipe, making it necessary to scrape the stem and bowl in order to clean it after having taken the pipe apart, whereas in my construction no scraping of the 35 stem is ever required. Should it be found that any material has accumulated on the wall of the stem which is in alignment with the groove of the receptacle, all that is necessary is to give the receptacle a turn about its 40 axis when it will cut any material automatically.

Other objects and advantages of my invention will be clear to those skilled in the art to which it relates.

45 What I claim is:

In pipes, a bowl having a tobacco chamber and a stem projecting from the bowl as an integral structure, said stem being provided with a bore entering from its outer end and terminating short of the tobacco chamber of the bowl to constitute a cylindrical chamber, a mouth piece having a stopper portion to fit the entrance of the cylindrical chamber and having a smoke duct from end to end, a tubular receptacle fitting said cylindrical chamber and having a closed end to lie against the end wall of said bore and having its other end located adjacent said stopper portion, said receptacle having an inwardly directed 50 longitudinal groove along its outer surface extending from end to end, said bowl having a smoke port leading from said tobacco chamber at a substantial distance from the bottom thereof to the adjacent end of said longitudinal groove, said receptacle at its end adja-

cent said stopper portion having a passage for smoke from said groove into the receptacle, and a short tube carried by said mouth piece projecting into said receptacle and registering with the smoke duct of the mouth piece.

WILLIAM GEORGE CLARK.
